UNITED STATES PATENT OFFICE

126,210

DESIGN FOR A FLOWER HOLDER

Agnes Muhl, Waco, Tex.

Application July 22, 1940, Serial No. 93,842

Term of patent 7 years

To all whom it may concern:

Be it known that I, Agnes Muhl, a citizen of the United States, residing at Waco, county of McLennan, State of Texas, have invented a new, original, and ornamental Design for a Flower Holder, of which the following is a specification, reference being had to the accompanying drawing, forming a part thereof.

Figure 1 is a plan view of the flower holder and Figure 2 is a cross section taken on line 2—2 of Figure 1 showing my design.

I claim:

The ornamental design for a flower holder, as shown.

AGNES MUHL.
